CLAIM

The ornamental design for a sensor housing assembly, as shown and described.

DESCRIPTION

FIG. 1 is a front perspective view of the claimed design for a sensor housing assembly;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines showing the remainder of the sensor housing assembly depict environmental structure and form no part of the claimed design.
